UNITED STATES PATENT OFFICE.

STERLING ELLIOTT, OF BOSTON, MASSACHUSETTS, ASSIGNOR TO THE ELLIOTT COMPANY, OF BOSTON, MASSACHUSETTS, A CORPORATION OF MAINE.

ADDRESSING-MACHINE.

SPECIFICATION forming part of Letters Patent No. 714,789, dated December 2, 1902.

Application filed August 23, 1900. Serial No. 27,854. (No model.)

To all whom it may concern:

Be it known that I, STERLING ELLIOTT, a citizen of the United States, residing at Boston, in the county of Suffolk and State of Massachusetts, have invented certain new and useful Improvements in Addressing-Machines, of which the following is a specification.

My invention relates to machines for printing addresses and other like matter which must be printed from a series of different plates, preferably stencil-plates; and my invention consists in constructing a machine which can be operated without the use of power and adapted for use in small offices; as fully set forth hereinafter and illustrated in the accompanying drawings, in which—

Figure 1 is a front elevation of the machine and its supporting table and case. Fig. 2 is a side elevation in part section. Fig. 3 is a plan view; Fig. 4, an enlarged plan of the central part of the machine; Fig. 5, an enlarged transverse section of the guard-frame on the line 5 5, Fig. 4; Fig. 6, a side view of the pusher; Fig. 7, a cross-section of the guide and slide ways with the pusher therein. Fig. 8 is a sectional view on the line 8 8, Fig. 4, showing the retarding device. Fig. 9 is an enlarged transverse section through the center of the machine. Figs. 10 to 12 are views illustrating the operation of the pawl for actuating the inking-cylinder.

The table A is suitably mounted and is provided with a receptacle B, Fig. 3, for printing-plates of any desired character, hereinafter termed "stencils," to be printed from, a receptacle C for stencil-plates which have been printed from, and intermediate printing apparatus D, and with means for transferring the stencils from one receptacle to another and for operating the printing apparatus, all of said parts being moved from a swinging lever or treadle E.

The receptacle B consists of two angle corner-pieces 1 1 and a back piece 2, which are set so as to receive between them the pile of stencil-plates of any suitable character, and these posts are arranged above a slideway x, adapted to receive the lowermost stencil of the pile, and upon guides 4 4, Fig. 7, slides a pusher R, which when carried to the position

shown by dotted lines y, Fig. 3, is opposite the outer end of the lowest stencil, so that when the pusher is carried to the position shown in full lines it shoves said stencil along the slideway from beneath the pile. When a second stencil is thus pushed out, it will push the first to its position in the printing apparatus. The forward movement of the third stencil pushes the first out of the printer, and the next movement carries the first into the receptacle C. The receptacle C has corner-posts 5 5 and a back post 6, like the receptacle B, but is arranged with its upper end below the slideway x, so that the stencils after entering the receptacle C and passing onto a table F may descend with said table, which slides vertically in the receptacle. The table is arranged to descend under the weight of the stencils moving downward as the number of stencils increases. Any suitable means may be employed to secure this result. As shown, there is a spring 7, Figs. 1 and 2, which is of such a character as to permit the gradual descent of the table, to which the lower end of the spring is attached. It is desirable to oil the pusher-guides, and yet it is objectionable to have the oiled surfaces where the oil can pass to the stencils. I therefore arrange the guides 4 4, Fig. 7, below the slideway x, and the pusher rests only on the guides, and its pushing-flange 8 is above but out of contact with the faces of the slideway, so that the stencils can move freely without being oiled. To prevent the stencils in rapid operations from being thrown out of the slideway, I use a friction device G, Figs. 4 and 8, which somewhat resists the passage of the stencils to the receptacle C. As shown, this device is a pin 9 in a socket below one of the side guides 10 of the slideway x, resting on a spring 12, so that in passing the stencil along the slideway the pin is depressed, creating such a resistance as prevents the too-rapid expulsion of the stencil. While I have shown this arrangement of receptacles and feed devices, any other suitable means may be employed.

The printing apparatus comprises a platen H below the path of the stencils, an impression device I, as a roller, above the said path and above the table or other support for the

card or strip to be printed, and means whereby the impression device may be brought down into the stencil to print through the openings in the stencil onto the card. With the impression device is combined means for supplying it with ink—as, for instance, a cylindrical linking-plate J—which rotates in contact with the roller I and which is suitably supplied at intervals with ink—as, for instance, by a hand-roller K, Fig. 1, which, with an ink-block K', is kept in a compartment of a case L, forming part of the support for the table A. Preferably the roller I and inking-cylinder J are supported to move together, and to this end they are mounted on a frame M, pivoted to studs 15 on the table A, the bracket 16 of the frame M, which carries the cylinder J, being pivoted to the lower part at 17 and provided with set-screws 18 and retaining-screws 19, whereby to properly adjust the cylinder in respect to the roller.

It is desirable to limit the area of stencil exposed to the printing-roller and the extent inked, and I therefore make use of a guard-frame N, Figs. 4 and 5, consisting of a rigid frame 20 and a thin metal plate bolted thereto and slit and bent to form thin inclined flanges 21 at the ends and inclined sides 22, with flat flanges, the edges of which are just so far separated as to expose only the perforated parts of the stencil. The flanges 21 22 are so elastic that they will yield, so that when the flanges move down into the stencil and the latter lies on the platen they will accommodate themselves to the stencil and to the roller I. The frame N must be lifted to permit the feed of the stencils and must descend with the roller I, and it is also desirable that either end be allowed to move vertically independent of the other, so as to accommodate it to any variations in the thickness or other irregularities of the cards or other matter printed. I thereby carry the frame N upon trunnions 23, each supported by a lever P, rocking on a shaft 44, extending through the studs 15, Figs. 4 and 9, and arms 24 of these levers extend to the rear and are perforated to receive loosely the ends of a cross-bar 25, to the center of which is attached a spring 26, connected at the upper end to a standard 27, Fig. 9. This spring tends to carry down the forward ends of the levers and the frame N, but permits either end to rise, while the guide-frame N can tilt freely on its trunnions. The frame N, therefore, is free to move vertically at either end to swing on its trunnions, while its flanges 22 23 are flexible and yield under pressure, thus insuring absolute contact with the stencil throughout however irregular may be the paper or card in which the stencil rests.

The movement of the inking-cylinder J is effected from the vibration of the frame M by means of a pawl Q, pivoted to the standard 27 and engaging pins 29 on the side of the cylinder, the descent of the latter bringing the pins successively into engagement with

the shoulder of the pawl, so that the further downward movement causes the cylinder to turn. The cylinder should not rotate when the roller I is stationary, as it would result in unevenly distributing the ink. I therefore provide the pawl Q with a projecting end or finger 30, which will extend over the pin which is beyond that engaged by the shoulder of the pawl, as in Fig. 11, so that on the further descent of the cylinder as the roller I engages the stencil the shoulder of the pawl will be disengaged from the pin of the cylinder, as shown in Fig. 12. The platen H, Fig. 9, is lifted and is then supported on an unyielding bearing to afford a proper support for the stencil while printing and then descends out of the way of the stencils while they are being moved into and out of position.

Different means may be employed for imparting the above-described movements to the different parts; but preferably all are moved by the vibration of the treadle-lever E through the means I will now describe.

The lever E is pivoted by a pin 31 between hangers 32 32, Figs. 1 and 9, and is connected by a toggle-lever 33 to an arm 39, extending downward from the frame M, so that as the lever E swings back the upper part of the frame M swings forward. At the same time the platen H, which is at the end of an arm 34, pivoted at 35 below the table, is lifted by a cam 36 on the lever E, which engages a roller below the platen, so that the roller I is carried down and the platen lifted simultaneously, and a firm support is afforded below the platen to resist the downward pressure on the latter, the cam 36 then being practically directly above the axis 31 of the lever E.

The levers P are operated to lift their forward ends by a cam 40 on an arm 41, carried by the lever E, said cam engaging a roller 42 on an arm 43, extending from the shaft 44, which carries arms 28, each of which is provided with a set-screw 28^a, resting on a projection of one of the levers P, Figs. 4 and 9. The arm 41 is provided with a cam-slot w, Fig. 9, which receives a roller 50 on an arm 51, extending from a sleeve 53, vibrating on a vertical pin 52, extending downward from the table A, and an arm 54 of said sleeve is connected with the pusher R by a link 55. As the lever E is rocked and the arm 41 rises and falls the sleeve 53 is thus vibrated to implement proper movement to the pusher.

The cards, envelopes, newspapers, or other matters to be addressed are properly set by means of a gage S, Figs. 3 and 9, adjustable on the table A. When it is necessary at any time to lift the guard-frame N out of its ordinary time, this may be done by rocking the shaft 44 by hand by means of a lever 56, Figs. 3 and 9. A rubber stop 60, Fig. 9, is arranged to limit the movement of the lever E by the contact therewith of the arm 41.

Without limiting myself to the precise arrangement or construction of parts shown, I claim—

1. The combination of the receptacles, stencil-feeding means, vibrating frame, impression-roller I, inking-cylinder J, pins projecting from the cylinder, and pawl Q having a shoulder and projecting end, substantially as set forth.
2. The combination with the stencil-feeding means, of a vibrating frame carrying an impression-roller, and an inking-cylinder supported by brackets constituting an adjustable part of said frame, substantially as set forth.
3. The combination of the vibrating frame, its impression device, slideway below said device, a guard-frame N, and means for supporting it movably, below the impression device, substantially as set forth.
4. The combination of the vibrating frame, its impression device, slideway below said device, and a guard-frame N pivotally supported below the impression device and means for moving said frame, substantially as set forth.
5. The combination of the vibrating frame, its impression device, slideway below said device, a guard-frame N, and independently movable levers supporting said frame at each end below the impression device, substantially as set forth.
6. The combination of the feeding-channel, impression device, and a guard-frame having flexible flanges 21, 22, substantially as set forth.
7. The combination of the slideway, vibrating frame and impression device, movable platen and intermediate independently-movable guard-frame, substantially as set forth.
8. The combination of the slideway, vibrating frame, impression device, movable platen, intermediate independently-movable guard-frame, and hand-lever for moving said frame, substantially as set forth.
9. The combination of the slideway, vibrating frame, impression device, movable platen,
- intermediate independently-movable guard-frame, levers P carrying said frame, a shaft 44 provided with arms and bearings making contact with said levers, a cross-bar between the levers, and a spring 28, substantially as set forth.
10. The combination with the receptacles and slideway, of the frame M, lever E pivoted at the upper end and having a foot-piece at the lower end, and intermediate toggle, substantially as set forth.
11. The combination with the receptacles, slideway, impression device and pusher, of the lever E pivoted at the upper end and with a foot-piece at the lower end, cam-arm 41, vibrating sleeve having an arm engaging the cam, and an arm connected to the pusher, substantially as set forth.
12. The combination with the impression device and means for reciprocating the same, of the frame N, levers P, P, shaft 44, arm 43, and the lever E carrying a cam engaging the cam-arm 43, substantially as set forth.
13. The combination with the impression device and means for reciprocating the same, of the frame N, levers P, P, shaft 44, pusher, arm 43, the lever E carrying the cam engaging the arm 43, and another cam and connections for operating the pusher, substantially as set forth.
14. The combination with the receptacles, stencil printing-plates, slideway, impression device and operating-lever E, of a movable platen, and cam on the operating-lever for moving the platen to and from the impression device, substantially as set forth.

In testimony whereof I have signed my name to this specification in the presence of two subscribing witnesses.

STERLING ELLIOTT.
